LONG-CHAIN UREA COMPOUNDS IN DETERGENT COMPOSITIONS

John Ross, Ramsey, N. J., assignor to Colgate-Palmolive Company, Jersey City, N. J., a corporation of Delaware

No Drawing. Application May 2, 1951,
Serial No. 224,264

12 Claims. (Cl. 252—137)

The present invention relates to new synthetic detergent compositions, and, more particularly to compositions of the type of the anionic sulfated and sulfonated detergents having improved properties.

There has been a considerable amount of research to discover substances or additives which aid the efficiency of detergent compositions. The problem is exceedingly complex, however, in view of the various physico-chemical mechanisms or properties and the like involved in the action of a detergent composition including suspension, interfacial tension, micellar structure, dispersion, foam stability, etc. and the general difficulty usually in determining the particular mechanism which is being altered by changes in the formulation of detergent compositions.

During recent years, synthetic detergents of the type of the organic sulfates and sulfonates have been developed which have properties which render them highly advantageous for certain uses. In general, the exploration for suitable additives or builders for synthetic detergent compositions of the type of the anionic sulfates and sulfonates has been directed by the requirements of increased foaming and/or detergency power. While the exact relationship, if any, between foaming and detergency is not known, it is highly desirable that these detergent compositions exhibit excellent foaming properties, in addition to a high level of detergency efficiency, particularly for consumer appeal and certain home and industrial uses. In view of the complex nature of both the foam and detergency phenomena, the character of such non-soap synthetic detergents, and the many other variables in detergent compositions, additives in general exhibit a certain degree of specificity of action.

Urea and certain lower derivatives thereof have been used with certain surface-active agents chiefly in large proportions as cheap and innocuous fillers and as solubilizing agents. Certain other derivatives have been used as intermediates in the manufacture of resins, plasticizers, emulsifying agents, pharmaceuticals, etc.

It has now been discovered that the presence of a substituted urea having a long-chain alkyl radical in detergent compositions consisting essentially of anionic sulphated and sulphonated detergents is effective to achieve a significant enhancement in surface-active properties such as detergency and foaming. More particularly, the improved detergent compositions consist essentially of water-soluble sulphated or sulphonated detergents, and as an organic builder a minor proportion of a higher alkyl substituted urea effective to enhance the action of the detergent composition in aqueous solution. These improvements are unique since such urea derivatives by themselves have poor foaming and deterging properties, and thus are valueless as cleaning agents per se.

Illustrative of the enhancing additives of the present invention are the higher alkyl substituted urea compounds characterized by limited water-solubility. These derivatives may be additionally substituted with low-molecular weight aliphatic radicals, such as lower alkyl and alkyloxy groups. The higher alkyl substituent may be branched

2

or straight-chain in structure; it comprises moreover such groups as octyl, decyl, dodecyl, keryl, pentadecyl, and hexadecyl, mixed long-chain alkyls derived from long-chain fatty materials, cracked paraffin wax olefins, polymers of monoolefins, etc. This higher alkyl substituent will generally be from at least about 8, generally up to about 18 carbon atoms, and preferably about 10 to about 14 carbon atoms.

Included within the ambit of the invention is the following preferred class of compounds suitable as additives which may be represented by the structural formula:

wherein R is a long-chain higher alkyl radical. Suitable examples of such compounds are octyl urea, decyl urea, dodecyl urea, cocyl urea wherein the "cocyl" substituent is a mixture of essentially long-chain alkyls derived from mixed coconut oil fatty acids, dodecyl urea wherein the dodecyl group is derived from a propylene tetramer, teradecyl urea, myristyl urea, pentadecyl urea wherein the pentadecyl group is derived from a propylene pentamer, hexadecyl urea, etc.

An additional suitable class is the polyalkyl substituted ureas having one alkyl group long-chain in structure as indicated, and at least one lower alkyl group. The lower alkyl groups should have a total generally of not in excess of about six carbon atoms. It is preferred that each lower alkyl group be not in excess of about three carbon atoms each. These polyalkyl derivatives may be symmetrical or unsymmetrical. Specific examples within this class are N dodecyl, N methyl urea; N dodecyl N' methyl urea; N dodecyl, N'N' dimethyl urea; N tetradecyl N' ethyl urea; etc.

A further class is the higher alkyl substituted ureas having at least one lower alkyloxy group, the carbon atom range being the same as with the lower alkyl groups. The alkyloxy group may be mono- or polyhydroxy in structure. Suitable examples are N dodecyl N' methyloxy urea; N dodecyl N' ethanol urea; N dodecyl N'N' diethanol urea; N dodecyl N' butanol urea; N tetradecyl N' 2, 3 dihydroxy propyl urea; etc.

These various urea derivatives may be prepared in any suitable manner and numerous processes for the production of alkyl ureas, mixed polyalkyl and alkyl-alkyloxy ureas, etc., and their analogues are well known in the art.

The novel compositions of the present invention contain as the active ingredient the anionic sulphated and sulphonated detergents, including suitable mixtures thereof. Included therein are the aliphatic sulphated or sulphonated agents, such as the aliphatic acyl-containing compounds wherein the acyl radical has about 8 to about 22 carbon atoms, and, more particularly, the aliphatic carboxylic ester type, containing at least about 10 and preferably about 12 to about 26 carbon atoms to the molecule. Among the aliphatic detergents, it is preferred to use the sulphated aliphatic compounds having about 12 to about 22 carbon atoms. As suitable examples of aliphatic detergents may be found the sulphuric acid esters of polyhydric alcohols incompletely esterified with higher fatty acids, e. g. coconut oil monoglyceride monosulphate, tallow di-glyceride monosulphate; the long chain pure or mixed higher alkylsulphates, e. g. lauryl sulphate, cetyl sulphate, higher fatty alcohol sulphates derived from coconut oil; the hydroxy sulphonated higher fatty acid esters, e. g. higher fatty acid esters of 2,3 di-hydroxy propane sulphonic acid; the higher fatty acid esters of low molecular weight alkyloxy sulphonic acids, e. g. oleic ester of isethionic acid; the higher fatty acid ethanolamide sulphates; the higher fatty

acid amides of amino alkyl sulphonics acids, e. g. lauric amide of taurine, and the like.

It is a feature of this invention that the effects are particularly enhanced with the alkyl aryl sulphonate detergents. These aromatic sulphonate detergents are also known in the art. They may be mononuclear or polynuclear in structure. More particularly, the aromatic nucleus may be derived from benzene, toluene, xylene, phenol, cresols, naphthalene, etc. The alkyl substituent on the aromatic nucleus may vary widely, as long as 10 the desired detergent power of the active ingredient is preserved.

More specific examples of suitable alkyl aromatic sulphonate detergents are the higher alkyl aromatic sulphonates. The higher alkyl substituent may vary in the 15 manner described for such groups in the higher alkyl urea additives. Thus, it may be branched or straight-chain in structure, and comprise decyl, dodecyl, keryl, mixed long-chain alkyls from polymeric lower monoolefins, etc. Preferred examples of this class are the higher alkyl mononuclear aryl sulphonates wherein the alkyl group has about 8 to about 22, and preferably about 20 12 to about 18 carbon atoms. More particularly, it is preferred to use the higher alkyl benzene sulphonates wherein the higher alkyl group averages about 12 to about 25 16 carbon atoms. For example, propylene may be polymerized to the tetramer and condensed with benzene in the presence of a Friedel-Crafts catalyst to yield essentially the dodecyl benzene derivative which is suitable for sulphonation to the desired sulphonate compounds.

These various anionic detergents are generally used in the form of their water-soluble salts, such as the alkali metal, alkaline earth metal, ammonium, amine, and alkylolamine salts. While the sodium, potassium, ammonium and alkylolamine (e. g. mono-, di-, and triethanolamine) salts are preferred ordinarily, other salts such as the lithium, calcium, and magnesium salts may be used if desired. For general use, it is ordinarily preferred to use the sodium and potassium salts. For certain specialized uses, it may be preferred to select the 40 ammonium and alkylolamine salts in view of their generally greater solubility in aqueous solution. The concentration of these water-soluble salts (including suitable mixtures thereof) in the detergent compositions of the present invention is generally at least about 10% by weight of total solids, and preferably from about 10-50%. With built compositions, particularly in particulate form, an active ingredient content of 10-50%, and preferably about 45 15-40% yields highly satisfactory results. Compositions with very high concentrations of these active ingredients are prepared for specialized uses generally. Thus in liquid detergent compositions, any suitable concentrations may be employed, e. g. 90% of total solids or about 20 to about 60% of the weight of the total liquid detergent composition.

The amount of the substituted urea additives in the detergent composition is generally minor in proportion to the weight of the active ingredient and effective in producing the desired improvements in detergency capacity and/or foaming power. Generally, the proportion of active ingredient to additive should be from about 50:1 to about 2:1. It is preferred that the additive be from about 5 to about 30% of the active ingredient. In particulate detergent compositions the additive will usually be from about 1/2 to about 15% by weight of the detergent composition. Particularly effective results have been achieved wherein the additives are present in amounts of the order of about 1 to 10% of the total detergent composition. It is preferred usually to use about 1-5% additive however. The optimum amount of additive and its ratio to the active ingredients will vary according to the specific materials, the contemplated field of application and manner of use.

The additives may be incorporated with the active ingredient at any point during the manufacturing process

at which subsequent operations will not adversely modify the properties of the detergent compositions. A variety of procedures which have proved to be convenient, economical, and productive of best results are: the additives may be added to a hot aqueous slurry of about 40 to 50% solids concentration comprising the active ingredient with vigorous stirring to form a smooth, uniform and homogeneous paste, the additives may be dissolved in a suitable solvent and added to the slurry of the active ingredient, a mixture or emulsion of the additives in water with a minor proportion of the active ingredient may be incorporated into the slurry, or the additive may be incorporated in the detergent composition by a post treatment to spray-dried detergent particles, etc.

Thereafter, these compositions may be prepared in the form of solutions, pastes or as dry or partially hydrated solid products, preferably in a finely divided condition. It is preferred to prepare the products in particulate form. Accordingly, the slurry of the detergent composition may be subjected to any suitable drying operations and converted to particle form. The mixture may thus be subjected to conventional spray-drying, roll-drying or drum-drying operations utilizing temperatures above about 212° F. to obtain homogeneous detergents particles.

The additives exert their primary detergency effects on an activation of the soil removal power. Such results may be illustrated by the application of soil removal tests, using a testing procedure which involves the uniform soiling, washing with particular detergent compositions at 110° F. ± 2 ° F., and drying of a large number of cotton swatches. The whiteness of the various test swatches is measured by a Hunter reflectometer. The units of soil removed may be calculated by subtracting the average reflectivity of unwashed control samples from the washed swatches. The results on soiled wool swatches may be determined using substantially the same testing procedure.

Table I indicates the percent increased reflectance as a measure of improved soil removal, on cotton and wool swatches using a standard detergent composition consisting essentially of 20% sodium salts of dodecyl benzene sulfonate (the dodecyl group being derived from a propylene tetramer), 40% sodium tripolyphosphate, 3% sodium carbonate and 37% sodium sulfate at 0.4% concentration in soft tap water, with and without added cocoyl urea additive. The percentages listed in the table for each concentration of additive represent the percent change in whiteness reflectance using as a standard the above detergent composition without organic additive. A (+) value indicates the approximate improved whiteness reflectance as a measure of improved soil removal and a (-) value represents decreased soil removal in comparison to the standard.

Table I

Amount of Additive, Percent	Percent Change in Soil Removal	
	Cotton Soil	Wool Soil
0.5	-2	+6
1.0	-2	+14
1.5	+10	+28
2.0	+28	+54
3.0	+23	+79
4.0	+32	+92
5.0	+27	+90
6.0	+19	+90
7.0	+23	+94
8.0	+13	+76
9.0	+7	+96
10.0	-5	+89

The marked improvement in soil removal due to the presence of the substituted urea additives is evident from the data. It is apparent that on cotton soil, optimum results are achieved using about 2-5% of the additive with this particular detergent composition. On wool soil, the

effects are much more marked, with synergistic improvement effected at all concentrations and optimum results at 3-10% additive. The significance of the presence of these additives is even more striking since the above compositions containing the additive and about 20% detergent is much more effective generally in soil removal than compositions containing for example 35% detergent without the additive.

However, for each specific type additive, as for each detergent composition, there is an optimum proportion or concentration which may be determined by routine tests. A few representative additives in the identical detergent composition referred to above yield the following results by the same procedure:

Table II

Additive	Percent	Percent Change in Soil Removal	
		Cotton Soil	Wool Soil
1. Dodecyl urea	2	+15	+30
	3	+34	+50
2. Decyl urea	4	+29	+56
	2	+10	+38
3. Octyl urea	3	+1	+15
	5	+10	+29
	7	+15	+42
	10	+30	+74

Another feature is that the improved results may be exhibited both in hard and in soft water, and over a wide range of washing concentrations. While additives in general exert widely variable effects in hard and soft water, the novel compositions of the present invention are effective in both types, thereby enlarging their field of application to a great degree. The wide range of suitable washing conditions under which the improved results are obtained is significant also since it permits economy of use and allows a wide latitude to the consumer and the like as to suitable quantities to be employed.

Table III illustrates the percent improvement in soil removal at 0.25%, 0.4%, and 0.75% concentrations of the self same detergent composition in hard water of 300 p. p. m. hardness using only 1.5% of dodecyl urea additive on cotton swatches.

Table III

Concentration of Detergent Composition	Percent Change in Soil Removal
0.25 percent	
0.40 percent	+10
0.75 percent	+6
	+9

The results are even more marked using other selected percentages of additives and wool swatches.

From the viewpoint of foaming generally, the novel compositions of the present invention are characterized by increased stability of the foam produced in washing operations in comparison to the foaming effects produced by compositions without the additive. The foam of the present compositions has good creaminess and consistency, does not readily break down by evaporation, has in general a longer drainage time, and contains an increased amount of liquid.

It has also been found that the present combinations tend to increase the tolerance of the detergent composition for the assimilation or holding in suspension of a maximum amount of dirt, grease, etc. with less foam loss than is found without the use of the desired additives.

In practical dishpan tests wherein greased dishes are washed by hand in a dishpan of water containing a small amount of the detergent composition, the compositions

of the present invention exhibit superior foaming properties. As increasing numbers of greased plates are washed, the foam decreases. The rate of foam decrease is considerably slower on solutions of the present compositions than with corresponding solutions of the detergent compositions without the desired additives.

Table IV discloses comparatively the average results in foam endurance or duration obtained in the dishwashing of various greased plates with two compositions. Formula A contains 25% sodium salts of coconut monoglyceride monosulfate detergent as the active ingredient, 10% diacid disodium pyrophosphate and 65% sodium sulfate. A second formula (B) has 3% dodecyl urea added thereto. The tests are conducted in hard water at 0.25% concentration at 115° F. with the number of greased plates washed by the formula A without additive being taken as a standard of 100%. The result with Formula B is tabulated in terms of percent of the standard.

Table IV

Composition	Foam Endurance in Dishwashing, percent
A	100
B	175

The unusual effect obtained by Composition B containing additive is evident from the data. It is clear that in the relationship set forth the additive achieves a synergistic enhancement in foam duration and resistance to greasy soil.

The activation of foaming power may also be illustrated quantitatively by a soil tolerance test. The procedure comprises conducting the pour foam test in the presence of a small amount of soil. The pour foam test is designed for comparative study of the relative foam stability of liquids and is set forth in U. S. Patent No. 2,315,983 to Ross and Miles. The foam height in millimeters of solutions tested in accordance with the Ross et al. patent at various time intervals is an indication of the foam stability in the presence of soil.

The above test is conducted at 0.25% concentration of detergent composition in distilled water, using separately three compositions. Composition I is the detergent formula set forth in Table I containing 20% sodium dodecyl benzene sulfonate, Composition II contains 1.5% dodecyl urea added to I, and Composition III has an active ingredient content of 35% and a corresponding reduction in the amount of sodium sulfate is made accordingly. The following results are achieved:

Table V

Composition	Foam Height			
	0 Min.	5 Min.	10 Min.	15 Min.
I	195	170	0	0
II	205	205	205	200
III	240	240	220	90

Thus it may be noted that Composition II containing the urea type additive exhibits a high level of foam stability for the full time interval, whereas the foam generated by Formula I with no additive collapsed completely within 5-10 minutes. The synergistic effect of the additive herein is all the more striking in relation to the effects achieved with Formula III containing a vastly increased active ingredient content.

It is common to employ various adjuvant materials in synthetic detergent compositions. The detergent compositions of the present invention may include any of these substances employed by the art in admixture

with such detergent compositions generally, provided the use of any such materials does not completely neutralize or remove the effect of the substituted urea type additives in the relationship set forth. These adjuvant builders or additives may be inorganic or organic in structure and may be mixed with the active ingredient in any suitable manner. Such conventional inorganic builders or additives as the various alkali metal phosphates (e. g. tri-polyphosphate, hexametaphosphate, tetracyclic phosphate), the alkali metal silicates, sulfates, carbonates, etc. may be employed in these compositions. Suitable organic materials such as sodium carboxymethylcellulose may also be employed herein. It is preferred that the detergents compositions in particulate form contain major amounts of alkaline builders, particularly the inorganic water soluble phosphates. The total amount of phosphate compounds should usually be a minimum of at least about 10%, and preferably from about 10 to about 80% by the weight of the detergent composition for optimum results. A detergent composition containing an amount of active ingredient of about 15 to 50% with the requisite minor proportion of substituted urea additives and about 20 to about 60% total phosphate compounds, particularly wherein sodium tripolyphosphate is present in substantial quantities exhibits highly desirable properties. In liquid detergents, the active ingredient should preferably be in the form of a highly water soluble salt, e. g. ammonium, mono-, di- and triethanol amine salts. The liquid detergent composition may be prepared in dilute or concentrated aqueous solution with or without the presence of a lower molecular weight aliphatic alcohol such as ethyl alcohol, propylene glycol, etc.

The following examples are additionally illustrative of the nature of the present invention and it will be understood that the invention is not limited thereto:

Example I

A detergent composition is prepared by forming about 40 a 60% solids slurry containing on a solids basis about 35% sodium propylene tetramer benzene sulfonate salt, 40% sodium tripolyphosphate, 15% sodium sulfate, 3% dodecyl urea, and the remainder minor amounts of sodium chloride, sodium hydroxide, sodium carboxymethylcellulose, etc. This slurry is agitated at about 140° F. in a conventional soap crutcher to form a homogeneous mixture. The slurry is submitted to spray-drying with heated air at a temperature of about 350° F. with a resultant moisture loss of about 40%. The resulting composition is recovered in the form of beads, and possesses a high degree of detergative and foaming properties in both hard and soft water.

Example II

The procedure of Example I is repeated with the modifications that the active ingredient consists essentially of the ketyl benzene sulfonate salt, the organic additive is the N tetradecyl N' methylol urea, and the slurry is roll dried at about 50 lbs. steam pressure to flake form. This composition also possesses highly desirable detergative properties.

Example III

Using the procedure of Example I an improved detergent composition is prepared from the following components: 20% sodium lauryl sulfate, 40% sodium tripolyphosphate, 38% sodium sulfate, and 2% dodecyl urea.

Example IV

Another suitable detergent composition is prepared by compounding 25% sodium coconut monoglyceride sulfate, 10% diacid disodium pyrophosphate, 62% sodium sulfate and 3% N decyl N' hydroxyethyl urea.

Other formulations productive of desired results are:

Example V

	Per cent
Sodium coconut alcohol sulfates	16
Sodium chloride	1
Sodium tripolyphosphate	38
Tetrasodium pyrophosphate	15
Sodium sulfate	27
N dodecyl N' hydroxyethyl urea	3

Example VI

	Per cent
Sodium dodecylbenzene sulfonate	9
Sodium lauryl sulfate	10
N dodecyl N' methyl urea	3
Sodium carboxymethylcellulose	0.5
Sodium carbonate	1.5
Sodium sulfate	20
Sodium tripolyphosphate	44
Tetrasodium pyrophosphate	12

Example VII

	Per cent
Higher fatty acid amides of taurine derived from coconut oil	25
Sodium sulfate	30
Sodium tripolyphosphate	42
Dodecyl urea	3

Certain general conclusions are apparent from the many tests which have been conducted to determine the effectiveness of the substituted urea additives in the relationship set forth. The most appropriate additive and its most effective concentration for each particular sulphonated or sulphated detergent composition may be suitably determined by routine controls. In each case the intended use (e. g. hard or soft water, rug shampoos or machine washing compositions, etc.) and the proper washing conditions should be taken into consideration in order to derive the maximum beneficial effects.

The term "consisting essentially of" as used in the definition of the ingredients present in the composition claimed is intended to exclude the presence of other materials in such amounts as to interfere substantially with the properties and characteristics possessed by the composition set forth but to permit the presence of other materials in such amounts as not substantially to effect said properties and characteristics adversely.

Although the present invention has been described with reference to particular embodiments and examples, it will be apparent to those skilled in the art that variations and modifications of this invention can be made and that equivalents can be substituted therefor without departing from the principles and true spirit of the invention.

Having described the invention what is desired to be secured by Letters Patent is:

1. An improved synthetic detergent composition consisting essentially of a detergent selected from the group consisting of the water-soluble anionic organic sulphate and sulphonate detergents and a minor proportion of a urea derivative represented by the formula:

wherein R is a higher alkyl radical of about 10 to about 14 carbons, said minor proportion being sufficient to improve the soil removal power thereof.

2. An improved synthetic detergent composition consisting essentially of water-soluble higher alkyl mononuclear aryl sulphonate detergent salts and in minor proportion from about 1 to about 10% of a urea compound represented by the formula:

wherein R is a higher alkyl radical, the amount of said urea compound being sufficient to enhance the effect of said detergent composition in solution.

3. An improved synthetic detergent composition in particulate form consisting essentially of a water-soluble higher alkyl aryl sulphonate detergent salt and a urea compound represented by the formula:

wherein R is a higher alkyl radical, the proportion of said sulphonate salts to urea compound being from about 50:1 to about 2:1 and sufficient to enhance the effect of said detergent composition in solution.

4. An improved heat-dried synthetic detergent composition consisting essentially of about 10 to about 50% water-soluble alkyl aryl sulphonate detergents, about 10 to about 80% water-soluble alkali metal phosphates, and a substituted urea compound represented by the formula:

wherein R is a higher alkyl radical, the amount of said urea compound being from about $\frac{1}{2}$ to about 15% and sufficient to enhance the effect of said detergent composition in solution.

5. An improved synthetic detergent composition consisting essentially of a water-soluble aliphatic sulphated detergent, and a urea compound represented by the formula:

wherein R is a higher alkyl radical, the proportion of said detergent to urea compound being from about 50:1 to about 2:1 and sufficient to enhance the effect of said detergent composition in solution.

6. A detergent composition consisting essentially of a water-soluble detergent selected from the group consisting of the anionic organic sulphate and sulphonate detergents, and a minor proportion of a compound selected from the group consisting of higher alkyl ureas having the formula:

wherein R is a higher alkyl radical, and their nitrogen-substituted lower alkyl and lower alkylol derivatives sufficient to improve the soil removal power thereof.

7. A detergent composition consisting essentially of a water-soluble detergent selected from the group consisting of the anionic organic sulphate and sulphonate detergents, and about $\frac{1}{2}$ to about 15% by weight of a compound selected from the group consisting of higher alkyl ureas having the formula:

wherein R is a higher alkyl radical, and their nitrogen-substituted lower alkyl and lower alkylol derivatives.

8. A detergent composition consisting essentially of a water-soluble detergent selected from the group consisting of the anionic organic sulphate and sulphonate detergents, and a minor proportion of a substituted urea derivative represented by the formula:

wherein R is an alkyl radical of about 8 to 18 carbon atoms sufficient to improve the soil removal power thereof.

9. A detergent composition consisting essentially of a water-soluble detergent selected from the group consisting of the anionic organic sulphate and sulphonate detergents, and a minor proportion of dodecyl urea sufficient to improve the soil removal power thereof.

10. A detergent composition consisting essentially of a water-soluble higher alkyl benzene sulfonate detergent, and about $\frac{1}{2}$ to about 15% by weight of a compound represented by the formula:

wherein R is an alkyl group of 10 to 14 carbon atoms.

11. A detergent composition consisting essentially of a water-soluble higher alkyl sulfate detergent, and about $\frac{1}{2}$ to about 15% by weight of a compound represented by the formula:

wherein R is an alkyl group of 10 to 14 carbon atoms.

12. A detergent composition consisting essentially of a water-soluble higher fatty acid monoglyceride sulfate detergent, and about $\frac{1}{2}$ to about 15% by weight of a compound represented by the formula:

wherein R is an alkyl group of 10 to 14 carbon atoms.
